SEWING MACHINE ATTACHMENT

Filed June 15, 1928

UNITED STATES PATENT OFFICE

ALBERT LITTLE, OF BOSTON, MASSACHUSETTS

SEWING-MACHINE ATTACHMENT

Application filed June 15, 1928. Serial No. 285,563.

This invention relates to sewing machine attachments and pertains more particularly to that class of attachments used for guiding the material to be stitched by the needle of the sewing machine. The principal object of the invention is to provide a pair of cooperating guide members of simple and economical construction adapted properly to position with certainty a piece of base material and two other pieces of fabric as they approach the stitching needle to be sewed with the edge of the base fabric lying between the margins of the other pieces.

The subject matter of the invention has especial utility when employed to guide the strips of fabric constituting after stitching the waist band of a garment such as men's trousers, in which a composite strengthening bend comprising a finished lining and a canvas reinforcement is to be sewed to a strip of material of the same character as the garment. The invention will accordingly be illustrated and described in connection with materials of this nature, and further objects, residing in the construction and arrangement of the attachments, will be apparent from the following description and will be pointed out in the appended claims.

A recommended embodiment of the invention is illustrated in the accompanying drawings, in which:

Fig. 1 is a plan view of a portion of a sewing machine equipped with the improved guides;

Fig. 2 is an enlarged section on the line 2-2 of Fig. 1 illustrating the arrangement of the guides and the positions of the fabric strips; and

Fig. 3 is a fragmentary section taken on the line 3-3 of Fig. 2.

The attachments comprise essentially a pair of cooperating guide members 4 and 5 preferably adjustably mounted with respect to each other upon the bed 6 of a sewing machine and in suitable proximity to the needle 7 carried in the needle bar 8. To permit adjustment of the guides toward and from each other, the guide plate 4 has a pair of transverse slots 9 receiving screws 10 and the guide

member 5 carries a mounting bracket 11 having slots 12 receiving screws 13.

The guide plate 4 preferably consists of a metal sheet having an upstanding flange 14 along its inner side, the plate being bent upwardly of the bed 6 along a line 15 parallel to said flange to provide a raised guide surface defining an underlying longitudinal cloth recess 16. The upper edge of the flange 14 is preferably inclined downwardly toward the needle end of the plate as indicated at 17, Fig. 3.

The other guide member 5 consists of a metal sheet in the form of a substantially flat sided sleeve inclined downwardly on its bracket 11 toward the needle 8 at substantially the same angle as the flange edge 17. The sleeve comprises a top part 18, an underlying portion 19 returned from the inner longitudinal folded edge 20 of the sleeve, and a bottom flap 21 folded inwardly as at 22 from the opposite longitudinal edge of the sleeve.

The underlying portion 19 serves as a fabric support and guide and extends outwardly so as to be disposed parallel to the top 18 with its outer edge 23 spaced a short distance from the fold 22. Similarly the flap 21 is disposed in spaced parallel relationship to the outer margin of the support 19.

The two guide members are so arranged with respect to each other that the inner fold 20 of the sleeve guide 5 overlaps the inner flanged margin of the guide plate 4, whereby the margins of the materials guided by the folded sleeve and the plate respectively will be fed toward the needle 7 for correct stitching. It will be observed from the foregoing and from the subsequent description of the arrangement of the fabrics to be stitched that the width of the multiply hem will be governed by the extent of the overlap of the guide members, and that said overlap may be adjusted by the screws 10 and 13.

As illustrated in Fig. 2, the materials to be guided by the attachment and stitched by the needle may include a strip of base material 24 which rests upon the guide plate 4 with its inner edge abutting and guided by the flange 14; a strip of lining material 25 fitting within and guided by the sleeve 5.

and preferably having an unstitched hem 26 along its inner edge abutting the fold 20; and a canvas reinforce 27 having its outer edge sewed to the lining as at 28 and having 5 its inner margin received within the recess 16 and guided by the raised platform of the plate 4.

When the materials thus arranged and 10 guided are fed toward the needle, it will be apparent that their overlapping margins will be correctly sewed together by any suitable 15 stitch performed by the needle and that in the resulting multiply hem the edge of the base material will be interposed between the 20 margins of the hemmed lining and the canvas reinforce respectively. In the finished 25 waistband the base material is folded and pressed over the canvas reinforce so that the edge thus formed is smooth and secure and 30 not excessively thick. It will be particularly observed that the edge of the canvas is not folded but that its rough edge serves as a sharp fold line for the base material and a firm edge at the top of the waistband. The 35 product produced by the operations herein set forth is more fully described and claimed in my copending application Serial No. 285,562 filed June 15, 1928.

The attachments embodying the present invention are simple and economical to manufacture, easily applied to any ordinary type of sewing machine, and readily adjusted to produce stitched seams of the desired width. The guides permit easy feeding of the material to the needle and properly and effectively position the three strips of material as they move toward the needle. Details of structure may be varied to suit particular purposes without departing from the essence 40 of the invention as defined in the following claims.

I claim:

1. Devices adapted to be attached to sewing machines to guide three strips of material to the needle to be stitched together, comprising a sleeve for positioning one of the strips and the body portion of the second strip, and a guide plate having an upstanding flange at its inner edge for guiding the 45 edge of the third strip and having a channel for guiding the inner edge of said second strip, whereby the three strips are fed to the needle with their inner edges overlapping and with the edge of the third strip between the margins of the other two strips.

2. Devices adapted to be attached to sewing machines to guide three strips of material to the needle to be stitched together, comprising a sleeve provided with a downwardly inclined guideway for one of the strips, and a guide plate having an upstanding flange along its inner edge disposed beneath the inner margin of said guideway and having a guide channel disposed beneath 50 said flanged edge, said channel being adapted

to receive and position the inner edge of a second strip of material which is connected along its opposite edge to the outer edge of the first-named strip and said flange being adapted to guide the inner edge of a third strip slideable on said guide plate, whereby the three strips are fed to the needle with their inner edges overlapping and with the edge of the third strip interposed between the margins of the other two strips. 70

3. Devices adapted to be attached to sewing machines to guide three strips of material to the needle to be stitched together, comprising a sleeve provided with a guideway for one of the strips, said guideway being inclined downwardly toward the needle, and a guide plate mounted in juxtaposition to said sleeve and having an upstanding flange along its inner edge arranged beneath and substantially parallel to the inner edge of 80 said guideway, the top of said flange being inclined similarly to the sleeve, and said plate being bent upwardly along said flanged edge to provide a guide channel beneath said flange and beneath the inner edge of said 85 guideway, said channel being adapted to receive and position the inner edge of a second strip of material which is connected along its opposite edge to the outer edge of the first-named strip and said flange being adapted to 90 guide the inner edge of a third strip slideable on said guide plate, whereby the three strips are fed to the needle with their inner edges overlapping and with the edge of the third strip interposed between the margins of the other two strips. 95

4. Devices adapted to be attached to sewing machines to guide three strips of material to the needle to be stitched together, comprising a sleeve formed of sheet metal and having its inner longitudinal margin returned from its inner edge to provide a guideway for one of the strips and a support for a second strip which is connected along its outer edge to the first-named strip, said guideway being inclined downwardly toward the needle, and a guide plate adjustably mounted in juxtaposition to said sleeve and having an upstanding flange along its inner edge arranged beneath and substantially parallel to the inner edge of said guideway, the top of 110 said flange being inclined similarly to the sleeve and adapted to slide transversely thereunder, said plate having a guide channel disposed beneath said flanged edge and beneath the inner edge of said guideway, said channel being adapted to receive and position the inner edge of said second strip and said flange being adapted to guide the inner edge of a third strip slideable longitudinally 115 on said plate, whereby the three strips are fed to the needle with their inner edges overlapping and with the edge of the third strip interposed between the margins of the other two strips. 120

5. Devices adapted to be attached to sewing machines to guide a plurality of strips of material to be stitched together with their margins overlapping one another, comprising a sleeve member having a bracket adapted to support the sleeve above the bed of the sewing machine and at an inclination thereto, said sleeve member being formed of sheet material and consisting of an elongate 10 upper central portion, a guide platform returned beneath the upper portion from its inner longitudinal edge and a downwardly and inwardly directed flange portion along its outer edge, the outer edge of said platform 15 being disposed in spaced parallel relationship to said flange portion, and a second guide plate adjustably mounted in juxtaposition to said sleeve member, said plate having an upstanding flange along its inner edge and 20 a guide channel disposed beneath said flanged edge, said plate flange and said channel being arranged beneath and substantially parallel to the inner folded edge of the sleeve member.

25 In testimony whereof I affix my signature.
ALBERT LITTLE.
